UNITED STATES PATENT OFFICE.

EDWIN G. VAN WIE, OF DETROIT, MICHIGAN, ASSIGNOR TO THE DETROIT STOVE WORKS, OF DETROIT, MICHIGAN, A CORPORATION OF MICHIGAN.

GAS-STOVE.

No. 843,644.

Specification of Letters Patent.

Patented Feb. 12, 1907.

Application filed January 16, 1906. Serial No. 296,398.

To all whom it may concern:

Be it known that I, EDWIN G. VAN WIE, a citizen of the United States of America, residing at Detroit, in the county of Wayne and State of Michigan, have invented certain new useful Improvements in Gas-Stoves, of which the following is a specification, reference being had therein to the accompanying drawings.

10 My invention relates to new and useful improvements in gas-stoves, and consists particularly in the construction of a closed top detachably fitting an open-top stove, whereby either natural or manufactured gas may 15 be used, as will be more fully hereinafter described, and set forth in the claims.

A gas-stove when desired to be operated with artificial gas is provided with an open top, while the odors from the unconsumed 20 gases and products of combustion from natural gas preclude such a construction for the use of natural gas. Heretofore stoves have been constructed with closed tops especially for natural gas, or else an open-top stove was 25 required to be converted into a closed-top stove in the following manner: The open-top grating was removed and a closed-top section of the same dimensions was inserted in its place. As this was too close to the 30 burners to be practical, the burners had to be lowered and then a flue had to be cut in the back of the burner-box or wherever possible to communicate with the flue of the stove and carry off the products of combustion and 35 unconsumed gases. Cutting this flue and lowering the burners is a difficult and expensive piece of work and in spite of it the stove was unsatisfactory, for the reason that the stove-flue was only large enough to carry off 40 the products from the lower burners and was not sufficiently large to carry off the added amount.

These difficulties I have entirely obviated by my invention, and open-top stoves may, if 45 desired, be manufactured exclusively and converted into closed-top stoves quickly and cheaply and are absolutely satisfactory in operation.

In the drawings, Figure 1 shows a top plan view of the ordinary open-top stove, and Fig. 2 a bottom plan view of my improved closed top. Fig. 3 is a vertical section on lines 3 3, Fig. 1; and Fig. 4 is a vertical section on lines 4 4 of Fig. 1 with the closed top in position,

the top shown in Fig. 4 being a slightly-modified construction: 55

A is the top casting of a stove, and A' is the ordinary open-top grating having four burners a'; but as many burners may be used as desired. The grating A' ordinarily rests on a 60 depressed inwardly-extending flange a, and the outer edge of the stove-top is provided with a downturned flange a².

B is the stove-flue for the lower or oven burners b and is provided with a preferably 65 oval flange B' for connection with a stovepipe.

C is a closed top of the form I preferably employ with ordinary lid-openings covered by lids c and having a downturned flange c' extending into engagement with the flange 70 a² and a downwardly-extending flange c³ resting upon the flange a. On the rear side of the top the flange c³ is cut away for a distance approximately equal to the width of the stove-flue, and short flanges c⁴ extend 75 from the ends of flange c³ to the sides of the flange B'. The space between the ends of the flange c³ and between the flanges c⁴ thus forms a flue for the burners a'. 80

Above the flange B' the top C is extended upwardly to form a stovepipe connection or sleeve C', and the front of this sleeve is spaced from the flange B' to allow sufficient communication from the top-burner flue. The flue in the sleeve C' is of sufficient size to allow 85 for the extra flue-space necessitated by the top burners, and the back of this sleeve preferably rests on the stove-top back of the flange B'.

In Fig. 4 I have shown a slight modification in which the flange c³ is omitted, the top being supported by a depressed flange D, resting on the stove-top and having its outer portion downturned at d to engage the flange a². 90

The supporting-flanges for the top are 95 made the length required to give the top sufficient clearance above the burners.

What I claim as my invention is—

1. The combination with a gas-stove, an open top therefor, top burners therein, an oven having a flue-passage, and a stovepipe-sleeve for said flue-passage, of a removable closed top, a downwardly-extending flange thereon engaging said open top and supporting said closed top, and a stovepipe-sleeve 105 integral with said closed top and larger than and alined with said stovepipe-sleeve for said flue-passage.

2. The combination with a gas-stove, an open top therefor, top burners therein, an oven having a flue-passage, and a stovepipe-sleeve for said flue-passage, of a removable closed top, downwardly-extending flanges thereon engaging said open top on the inside and outside of the edge thereof and supporting said closed top, and a stovepipe-sleeve for said closed top larger than and alined

with the stovepipe-sleeve, for said flue-passage.

In testimony whereof I affix my signature in presence of two witnesses.

EDWIN G. VAN WIE.
